UNITED STATES PATENT OFFICE.

LOUIS A. BAUDOIN, OF CHICAGO, ILLINOIS, ASSIGNOR TO EDWARDS & LOOMIS CO., OF CHICAGO, ILLINOIS, A CORPORATION OF ILLINOIS.

BAG-SEWING MACHINE.

1,111,877.

Specification of Letters Patent.

Patented Sept. 29, 1914.

Application filed August 5, 1912. Serial No. 713,471.

To all whom it may concern:

Be it known that I, LOUIS A. BAUDOIN, a citizen of the United States of America, and a resident of Chicago, county of Cook, State of Illinois, have invented certain new and useful Improvements in Bag-Sewing Machines, of which the following is a specification.

The main objects of this invention are to provide an improved construction in bag sewing devices, in which after the bag is filled it is caused to move past a sewing machine for the purpose of permitting the bag to be sewed; to provide improved means for obtaining a relative adjustment of the sewing mechanism and the bag conveyer so as to accommodate bags of various sizes; and to provide improved means for controlling the mechanism which operates the conveyer and the sewing mechanism.

An illustrative embodiment of this invention is shown in the accompanying drawings, in which:—

Figure 1 is a plan view of a specific form of the device constructed according to this invention. Fig. 2 is a sectional elevation taken on the line A—A of Fig. 1. Fig. 3 is a rear end view. Fig. 4 is an enlarged sectional detail of the clutch mechanism, the section being taken on the line B—B of Fig. 3. Fig. 5 is an enlarged side elevation of the clutch mechanism as viewed from the plane of the line C—C of Fig. 3.

In the construction shown in the drawings, a supporting frame 1, on which the operating mechanism is supported, is arranged adjacent to a pit 2 suitable for the operator to stand in while operating and feeding the machine.

A traveling platform or conveyer belt 3 of suitable design is mounted in the pit 2 so that its upper surface lies in substantially the same plane with the surrounding floor. The conveyer is fixed in its relation to the supporting frame with respect to vertical adjustment. The upper lap of the conveyer belt 3 is maintained against sagging, when carrying its load, by a plurality of closely spaced rollers 38 journaled in the bars 39.

Suspended over the conveyer 3 is a sewing machine head 4 which carries the sewing mechanism. The head 4 is supported from frame work 5 by means of the rocker

arms or bars 6, arranged in pairs horizontally and vertically. These arms are fulcrumed at 6' to the supporting frame 5 and are adapted to be shifted in a vertical direction for the purpose of adjusting the sewing machine head 4 relatively of the conveyer, whereby the device is adapted to be adjusted for sewing bags of various heights.

Driving connections are made from the countershaft 22^A to the conveyer 3 and the sewing mechanism in the head 4, said shaft 65 being driven by the belt 8 connected to the pulleys 9 and 14. Power is transmitted to the sewing mechanism by means of the belt 7, connecting the pulleys 9^A and 11 operating over the idlers 10. The countershaft 22^A 70 is connected to a second countershaft 23^A by means of sprocket wheels 22 and 23 and sprocket chain 26 from which the conveyer pulley 29 is directly driven by means of the sprocket chain 27 operating over the sprocket 75 wheels 24 and 25. The relative size of the pulleys 9^A and 11 and the several sprocket wheels is such as will cause the conveyer and sewing mechanism to operate at the proper speeds to effect the sewing of the bag. 80

The belt 12 connects a pulley 13 with any suitable source of power, the rotation of which is transmitted to the pulley 14 when the pulleys 13 and 14 are shifted so as to cause the engagement of the opposed clutch 85 faces formed thereon. The pulley 14 has a leather disk 16 secured to its inner face, against which the face 13^A of the pulley 13 bears when the pulley 13 is shifted toward the pulley 14. The pulleys 13 and 14 are loosely 90 mounted on the shaft 15 carried by the bracket 15^A secured to an adjacent part of the supporting frame.

Mechanism for shifting the pulley 13, to cause the engagement of the clutch faces, 95 comprises an arm or part 17 shiftably supported on the bracket 15^A and having an inclined pad or plate 18 at the end thereof, which, when the arm 17 is shifted, bears against the member 19 and urges the pulley 100 13 toward the pulley 14 so as to cause the engagement of the clutch faces. The arm 17 is normally shifted by the spring 17^A, so as to cause the pad 18 to be disengaged from the member 19, and thereby permit the disengagement of the clutch faces 13^A and 16. The shifting of the arm 17 against the action of the spring 17^A, to cause the engage- 105

ment of the clutch faces, is controlled by a rod 20 rotatably mounted at the base of the frame and extending from adjacent to the front edge of the conveyer to the rear part 5 of the supporting frame. Transversely disposed arms 20^A and 20^B are connected to opposite ends of the rod 20, the arm 20^A being connected to the arm 17 by the link 21 and the arm 20^B having a treadle 20^C secured thereto by means of which the rod 20 is 10 rotated through the depression of the arm 20^B for the purpose of shifting the arm 17 to cause the engagement of the clutch faces on the pulleys 13 and 14.

15 Adjustment of the sewing head 4 with respect to the platform 3 and the bag carried thereby is obtained by means of the pair of blocks 30 and 31 arranged one above the other and 20 connected horizontally between the arms 6, which are arranged in two pairs one above the other. The arms are all of substantially equal length between their respective points of pivoting to the frame and to the sewing 25 mechanism. Each block is provided with shoulders or pins 32 on both ends which extend through the slots or notches 32' in the arms 6. Vertically disposed guideways 33 are arranged on the supporting frame for 30 the purpose of receiving the pins 32 and guiding the blocks in their vertical movement.

A screw 34 is rotatably mounted in the frame 5 and has threaded engagement with 35 the blocks 30 and 31 whereby in turning said screw will cause a vertical shifting of the arms 6. A crank or handle 36 is attached to the screw 34 by means of which it is turned. The use of the vertical pairs of 40 arms insures that when the head 4 is shifted it will remain substantially upright and parallel to the same vertical plane for all positions and the use of horizontal pairs of arms insures greater rigidity.

45 The operation of the device is as follows: The sewing machine head 4 is adjusted to the desired position above the conveyer to insure the proper sewing of the bags, the adjustment being conveniently and quickly 50 made by the turning of the screw 34. A filled bag 37 is then set upon the conveyer and the treadle 20^C depressed which pulls the pad 18 downward and forces the clutch faces of the pulleys 13 and 14 into engagement with each other. The engagement of 55 these clutch faces causes the rotation of the pulley 14 thereby driving the countershaft 22^A which causes the conveyer to move and the sewing mechanism to operate on the bag 60 as it passes. The treadle is held depressed until the bag has reached the other end of the conveyer when it is released while the operator reaches for another bag.

Although but one specific embodiment of 65 this invention has been herein shown and

described, it will be understood that numerous details of the construction shown may be altered or omitted without departing from the spirit of this invention as defined by the following claims.

70

I claim:

1. A bag sewing device, comprising a supporting frame; a conveyer adapted for carrying filled bags; sewing mechanism adapted to sew the mouths of the bags while 75 carried by said conveyer; means for operating said sewing mechanism and said conveyer; a pair of arms fulcrumed on said frame one above the other on horizontally disposed axes, and carrying said sewing 80 mechanism hinged to each of said arms; and means for shifting said arms vertically for adjusting said sewing mechanism relatively to said conveyer.

2. A bag sewing device, comprising a supporting frame, a conveyer mounted in fixed vertical relation to the frame and adapted to carry filled bags, sewing mechanism adapted to sew the mouths of the bags while carried by said conveyer, means for operating 85 said mechanism and said conveyer, a pair of arms fulcrumed on said frame intermediate of their ends and each hinged to said sewing mechanism at its outer end, and a screw rotatably mounted on said frame 90 and having threaded connection with said arms at their inner ends whereby said sewing mechanism is adapted to be adjusted 95 vertically relatively of said conveyer.

3. A bag sewing device, comprising a supporting frame; a conveyer mounted in fixed vertical relation to the frame and adapted to carry filled bags; sewing mechanism adapted to sew the mouths of the bags while carried by said conveyer; means for operating 100 said mechanism and said conveyer; a plurality of rocker arms fulcrumed on said frame in pairs vertically and horizontally and having said sewing mechanism carried 105 at the outer ends thereof; horizontally disposed blocks mounted between said pairs of arms; vertical guideways on said frame; shoulders on said blocks adapted to engage said guideways; said arms being slotted at their inner ends to receive said shoulders; 110 and a screw rotatably mounted on said frame having threaded engagement with said blocks and adapted when turned to move said blocks in a vertical direction whereby said sewing mechanism is adjusted relatively 115 of said conveyer.

4. A bag sewing device, comprising a supporting frame; a conveyer adapted for carrying filled bags along said frame; sewing mechanism carried by said frame and having movement relatively to said frame toward and from said conveyer, and adapted 120 to sew the mouths of the bags while carried by said conveyer; and a pair of arms pivoted to said frame and arranged parallelly 125 130

one over the other and projecting over the said conveyer to support the said sewing machine in an upright position during its movement toward and from said conveyer,

5 said arms being of substantially equal length between points of pivoting to the frame and to the sewing mechanism respectively.

Signed at Chicago this first day of Au-
gust, 1912.
